C. FAYER

ELECTRICAL HAIR CURLING APPARATUS

Filed June 18, 1925

INVENTOR
CHARLES FAYER

BY Walton Harrison
ATTORNEY

UNITED STATES PATENT OFFICE.

CHARLES FAYER, OF FLUSHING, NEW YORK, ASSIGNOR TO WAPPLER ELECTRIC COMPANY, INC., A CORPORATION OF NEW YORK.

ELECTRICAL HAIR-CURLING APPARATUS.

Application filed June 18, 1925. Serial No. 37,921.

My invention relates to electrical hair curling apparatus, my more particular purpose being to provide a device of this character having certain specific advantages 6 hereinafter set forth.

More particularly stated I seek to produce an electrical hair curling apparatus in which I employ a number of separate heating units, connected preferably in parallel with each 10 other relatively to the source of electrical supply.

By use of my improved apparatus, connected as hereinafter described, I attain a considerable number of specific advantages, 15 among which are the following:

First. It is rendered practicable to construct and operate a large number of heating units all of them heating uniformly under all practicable working conditions.

Second. That it is practicable to vary within wide limits the number of heating units actually employed from time to time, changes in the number of units having relatively little effect upon the action of the several individual units actually in operation.

Third. That by means of my improved apparatus the dangers of arcing and sparking, due to electrical short circuiting or to poor connections, are avoided or at least reduced to a minimum.

Fourth. That owing to the construction and operation of the apparatus, the danger of a shock to the person whose hair is to be treated is greatly reduced, or prevented 35 altogether.

Reference is made to the accompanying drawing forming a part of this specification, and in which the figure is a side view, partly sectional and partly diagrammatic, illustrating my improved electrical hair curling apparatus and indicating the manner in which it is used.

Mounted upon a wall 7 are brackets 8 supporting a conduit tube 9, the latter carrying 45 a distributing head 10 having the proximate form of a bell, as indicated in Figure 1.

A step down transformer is shown at 11, and in this instance is a transformer of the so-called shell type. However, any other 50 appropriate form of step down transformer may be used, if of sufficient capacity to supply an adequate amount of current for each and all of the heating units as hereinafter described. In practice, by making the trans-

former rather large it is an easy matter to 55 render the secondary voltage substantially constant independently of the number of heating units energized from time to time while the transformer is in active use.

The transformer 11 is energized by aid 60 of a pair of primary conductors 12, 13, controllable by a switch 14.

Connected with the transformer 11 are a pair of secondary conductors 15, 16. Connected with the conductor 16 are a number 65 of small hand switches 17, 18, 19. While only twelve of these switches here shown the number may readily be larger, say from fifteen to eighteen.

Connected with these switches 17, 18, 19, 70 are conductors 20, 21, 22, which may be in the form of either wires or conducting cords.

The bell 10 carries a ring 23 of metal or other conducting material, and also carries a ring 24 of insulating material whereby the 75 ring 23 is insulated. The ring 23 is connected with the secondary conductor 15 above mentioned and is provided with a number of binding posts 25 to facilitate making electrical connections.

A number of sectors 26, 27, 28, each made of metal or other conducting material, are arranged in the form of a circle and separated by spacing sectors 29 of insulating material.

Any number of these sectors 26, 27, 85 28, may be employed, the number being the same as that of the wires 20, 21, 22. The sectors 26, 27, 28, are each provided with a binding post 29, there being as many of

these binding posts as there are of the binding posts 25. It will be noted that while each binding post, together with the sector such as 26, 27, 28, upon which it is mounted, is energized by some one of the conductors 20, 21, 22, whereas all of the binding posts 25, together with the single ring 23, upon which they are all mounted, are energized by means of the single conductor 15.

I provide a number of double conducting cords 30, 31, 32, for conveying current to 100 the heaters, there being as many of these double cords and as many heaters as there are individual conductors 20, 21, 22.

Each double cord 30, 31, 32, is provided with two branches 30^a, 30^b, leading to a pair 105 of binding posts 25, 29, above described.

I do not limit myself to the precise mechanism here shown, as variations may be

made therein without departing from my invention, the scope of which is commensurate with my claims.

I claim:

- 5 1. An electrical hair curling apparatus comprising a member of conducting material, a plurality of other members of conducting material insulated from each other and from said first mentioned member of 10 conducting material, a plurality of twin conductors for energizing individual hair curlers, each twin conductor being bridged across from said first mentioned member of 15 conducting material to some one of said second mentioned members of conducting material, a plurality of separate conductors, each connected with some one of said second mentioned members of conducting material in order to energize the latter, and switch 20 mechanism controllable by the operator for closing circuits through said twin conductors.

2. In an electrical hair curling apparatus the combination of a conduit tube, means for 25 supporting said conduit tube, a distributing head carried by said conduit tube, a ring of conducting material supported by said distributing head, a plurality of sectors insulated from each other and arranged in 30 the form of a ring concentric to said first mentioned ring and supported by said distributing head, a plurality of twin conductors each bridged across from said ring of 35 conducting material to some one of said sectors, a conductor connected with said ring of conducting material, a plurality of conductors connected with said sectors, and switch mechanism connected with last mentioned conductors and controllable by the 40 operator for energizing them individually.

3. In an electrical hair curling apparatus comprising a ring of conducting material, means for supporting said ring of conducting material, a conductor connected with said ring of conducting material, a plurality of twin conductors each connected with said ring of conducting material, and an electric mechanism connected with all of said 45 twin conductors and controllable by the operator for completing circuits independently of each other through said twin conductors.

4. In an electrical hair curling apparatus

the combination of a conduit tube, means for supporting said conduit tube, a distributing head carried by said conduit tube and having a bell form, a ring of conducting material located within said distributing head, twin conductors connected with said ring, a plurality of separate sectors connected with said twin conductors, said sectors being insulated from each other and formed into a ring concentric with said first mentioned ring and supported by said distributing head, a plurality of separate conductors connected severally with said sectors, and switch mechanism connected with said separate conductors and controllable by the operator, in order to energize said twin conductors independently of each other.

5. An electrical hair curling apparatus comprising a member of conducting material for distributing electric currents, connections to said member of conducting material, a plurality of other members of conducting material insulated from each other and from said first mentioned member of conducting material, and switch mechanism connected with said second mentioned conductors and controllable by the operator for completing circuits, independently of each other, through said second mentioned conductors.

6. An electrical hair curling apparatus comprising a ring of conducting material, means for supporting said ring of conducting material, a conductor connected with said ring of conducting material for energizing the latter, a plurality of separate sectors formed into a ring which is concentric to said first mentioned ring, said sectors being insulated from said first mentioned ring and from each other, twin conductors each connected with said first mentioned ring and with a sector of said second mentioned ring, and switch mechanism connected with all of said twin conductors and controllable by the operator for closing circuits, independently of each other, through said twin conductors.

Signed at Long Island City, in the county 100 of Queens and State of New York, this 15th day of June 1925.

CHARLES FAYER.
